DESIGN FOR A HEATER CABINET

Mervin F. Cotes and Walter C. Schneider, Lansing, Mich., assignors to Motor Wheel Corporation, Lansing, Mich., a corporation of Michigan

Application May 10, 1937, Serial No. 69,278

Term of patent 3½ years

To all whom it may concern:

Be it known that we, Mervin F. Cotes and Walter C. Schneider, citizens of the United States, residing at Lansing, in the county of Ingham and State of Michigan, have invented a new, original, and ornamental Design for a Heater Cabinet, of which the following is a specification, reference being had to the accompanying drawing, forming a part thereof.

In the drawing:

The figure is a perspective view of a heater cabinet embodying our new design. Both ends of the cabinet are identical, and the back of the cabinet is plain.

We claim:

The ornamental design for a heater cabinet as shown and described.
